J. MUTH.
ENVELOP SEALING ATTACHMENT FOR STAPLING MACHINES.
APPLICATION FILED JAN. 22, 1914.

1,109,355.

Patented Sept. 1, 1914.

UNITED STATES PATENT OFFICE.

JOHN MUTH, OF NORWALK, CONNECTICUT, ASSIGNOR TO THE E. H. HOTCHKISS COMPANY, OF NORWALK, CONNECTICUT, A CORPORATION OF CONNECTICUT.

ENVELOP-SEALING ATTACHMENT FOR STAPLING-MACHINES.

1,109,355.

Specification of Letters Patent.

Patented Sept. 1, 1914.

Application filed January 22, 1914. Serial No. 813,686.

To all whom it may concern:

Be it known that I, JOHN MUTH, a citizen of the United States, residing at Norwalk, county of Fairfield, State of Connecticut, have invented an Improvement in Envelop-Sealing Attachments for Stapling-Machines, of which the following is a specification.

This invention relates to stapling machines generally and has for its object to provide an attachment therefor that will adapt the machine for use as an envelop sealer.

It is of course well understood that envelopes sealed by means of gummed flaps may be readily opened by an expert and re-sealed so as to avoid detection and that even the use of sealing wax does not afford protection against the opening of envelopes and tampering with the contents and then re-sealing so neatly that the fact of opening will not be discovered.

My present invention enables me to provide a simple and inexpensive mode of sealing envelopes that will insure absolute privacy for their contents, as envelopes sealed in the manner I am about to describe cannot be opened without cutting or tearing the envelop itself, so as to show beyond a doubt that it has been tampered with.

My invention is applicable to any style of stapling machine which drives and clenches a staple by means of a single actuation of a plunger. I have shown it as applied to a Hotchkiss machine which severs a staple from a strip and drives and clenches it by an actuation of a spring controlled plunger and feeds the strip forward, placing another staple in position for use, by the return movement of the plunger.

In the accompanying drawing forming a part of this specification, Figure 1 is a perspective of a Hotchkiss stapling machine with my novel attachment applied thereto and illustrating the manner of placing an envelop in position for sealing; Fig. 2 a plan view of the anvil of the machine with the attachment in place; Fig. 3 an elevation corresponding with Fig. 2; Fig. 4 a view of the inner end of the carrying rod of the attachment; Fig. 5 a detail view as seen from the left in Fig. 2; Fig. 6 a detail sectional view showing a spring controlled locking plunger for retaining the hinged arm of the machine in the raised position; Fig. 7

a detail view partly in section, showing a staple in position to be severed, driven and clenched; Figs. 8 and 9 are plan views of envelopes sealed by staples applied by means of a machine using my novel attachment, and Fig. 10 is a detail view on an enlarged scale showing a staple clenched in the sealing flap and under ply of an envelop.

10 denotes the anvil of the machine, 11 the hinged arm, which carries the operative parts, 12 the plunger and 13 a spring which normally retains the plunger in the raised position. For convenience in inserting an envelop, I have shown the boss to which the arm is hinged as provided with a spring controlled locking plunger 14, which may or may not be used, as preferred. This plunger has a rounded end which passes slightly under the arm when it is in the raised position, as in Fig. 1, and retains it there, the power of the spring however being easily overcome when it is desired to lower the arm after the envelop has been placed in position to receive a staple.

The attachment comprises simply a carrying rod 15 and a clenching arm 16 hinged to the outer end thereof to swing vertically toward and away from the anvil, for a restricted distance. The outer end of the clenching arm is shown as rigidly secured to a vertically swinging plate 17, the lower edge of which lies in a slot in the carrying rod and is pivoted thereto as at 18. The plate is shown as provided with a stop shoulder 19 which is adapted to engage the top of the carrying rod and limit the upward swing of the clenching arm. The inner end of the clenching arm is preferably off-set as shown in Fig. 2, for convenience in inserting it under the under ply of an envelop, as will be more fully explained, and is provided on its upper face with a clenching recess 20 which co-acts with the plunger to clench a staple in the usual manner when it is driven by the plunger.

As a convenient means of securing the attachment to the machine a hole 21 is drilled in the side of the anvil which receives the end of the carrying rod. The end of the carrying rod is provided with a slot 22 which receives a stop pin 23 to definitely position the attachment and place the clenching recess accurately in alignment with the plunger. The attachment is rigidly

secured in place by a set screw 24 in the anvil which engages a recess 25 in the side of the carrying rod (see dotted lines, Fig. 4).

The operation is as follows: The sealing flap of the envelop is preferably moistened in the usual manner, although this is not essential. The sealing flap is turned outward as in Fig. 1 and is passed under the hinged arm which is retained in the raised position by the locking plunger. The inner end of the clenching arm, which is provided with the clenching recess, is passed under the under ply of the envelop, then the sealing flap is placed over the under ply in the usual manner, then the hinged arm is lowered upon the sealing flap and a staple is cut off and driven through the sealing flap and the under ply of the envelop and clenched on the under side thereof as clearly shown in Fig. 10. In sealing small envelops a single staple may be placed at the center, as shown in Fig. 9. In sealing larger sized envelops three staples or more are preferably used, as in Fig. 8. When three staples are used each under ply of the envelop is secured to the sealing flap by a clenched staple driven through both the flap and the ply and clenched on the under side of the ply so that the envelop cannot possibly be opened without slitting it or tearing out the staple or staples.

Having thus described my invention I claim:

1. The combination with the anvil of a stapling machine provided with a longitudinal opening having a stop pin therein and a transverse screw-threaded opening; of a

horizontal carrying rod having its inner end provided with a slot to receive the stop pin when inserted in the longitudinal opening and its outer end provided with a longitudinal slot; a clamping screw operating in the transverse screw-threaded opening to engage the carrying rod; a vertically swinging plate pivotally mounted within the outer slot in the carrying rod and provided with a stop shoulder to engage the carrying rod to positively limit the upward movement of said plate, and a vertically swinging clenching arm having its outer end rigidly secured to the plate and its inner end off-set laterally over the anvil and having upon its upper surface a clenching recess.

2. An attachment for a stapling machine, comprising a carrying arm having its inner end secured to the anvil of the machine and its outer end provided with a longitudinal slot, a vertically swinging plate pivotally mounted within the longitudinal slot and provided with a shoulder to engage the carrying arm to positively limit the upward movement of said plate, and a vertically swinging clenching arm rigidly secured to the pivoted plate and having its inner end laterally off-set over the anvil of the machine and provided upon its upper surface with a clenching recess.

In testimony whereof I affix my signature in presence of two witnesses.

JOHN MUTH.

Witnesses:

Wm. A. CURTIS,
EDWARD BURNS.
